UNITED STATES PATENT OFFICE.

MARSHALL T. GOFORTH, OF SUGARLAND, TEXAS.

COTTON PACKER.

Application filed October 19, 1920. Serial No. 417,998.

To all whom it may concern:

Be it known that I, MARSHALL T. GOFORTH, a citizen of the United States, residing at Sugarland, in the county of Fort Bend and 5 State of Texas, have invented a new and useful Cotton Packer, of which the following is a specification.

This invention relates to presses or cotton packing machines, the primary object 10 of the invention being to provide a press having a vertically reciprocating plunger wherein the construction of the device is such as to eliminate any side motion of the plunger during the operation thereof.

15 A further object of the invention is to provide a press of this character wherein the plunger operates in a true vertical plane to cause the cotton engaging extremity thereof, to exert an even pressure on the cotton during the packing operation.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawing:

Figure 1 illustrates a side elevational view of a press constructed in accordance with 35 the present invention.

Figure 2 is a sectional view taken on line 2-2 of Figure 1. Figure 3 is a plan view. Figure 4 is a detail view of the operating means. Figure 5 is a diagrammatical view 40 disclosing the positions of the operating gear and shaft connecting the operating gear with the connecting rod at the initial movement of the operating gear. Figure 6 is a diagrammatical view disclosing the positions of the operating gear and the shaft with respect to the plate upon one quarter movement of the gear. Figure 7 is a diagrammatical view disclosing the positions of the operating gear and its shaft when the operating gear has moved one half of the distance. Figure 8 is a diagrammatical view disclosing the positions of the gear and shaft when the operating gear has completed three-fourths of its movement.

55 Referring to the drawing in detail, the reference character 5 designates the base of

the frame which includes uprights 6 that have the horizontal bars 7 mounted thereon, which bars 7 support the operating means to be hereinafter more fully described. 60

Bolted to the base 5 is the bale form 8 which comprises a plurality of spaced members secured together by means of the bars 9, so that when pressure is brought to bear on the cotton within the form 8, any possibility of bulging of the form is absolutely prevented.

A plate 10 is secured to one of the bars 7, and as shown, this plate is provided with an internal gear 11, which gear meshes with 70 the teeth of the pinion 12 mounted on the shaft 13 that is carried on one end of the arm 14, which in turn is secured to the shaft 15. The number of teeth of the plate 10 and pinion 12 may be varied according 75 to the size of the machine, but it is to be understood that the ratio of teeth should be two to one.

This arm 14 is weighted at its free end, to cause an even and steady rotation of the 80 pinion 12 within the stationary plate 10. A pinion 16 is also mounted on the shaft 15, and this pinion 16 meshes with a relatively small pinion 17, which is mounted on the inner extremity of the shaft 18 which 85 also supports the pulleys 19 and 20, the pulley 20 being loosely mounted on the shaft so that the belt 21, when operating over the pulley 20 will cause the machine to idle, but when the belt is shifted to the pulley 19 90 as by means of the belt shift lever 22, the machine is brought into operation.

A support 23 carrying a shaft 23' is carried by the pinion 12 and this bearing member provides means of connection between 95 the connecting rod 24 and the arm 14, mounted on the opposite side of the plate 10 so that movement of the arm 14 will produce a relative movement of the connecting rod 24. This connecting rod 24 has its lower 100 extremity bolted to the plunger 25, which plunger is of a size to move within the form 8, when the same descends, there being provided guide rods 26 operating through suitable tubular guideways 27 supported by the 105 horizontal bars 7, thereby insuring a true vertical movement of the plunger.

The operation of the device is as follows:

Rotary motion is imparted to the shaft 18, through the belt 21 operating over the 110 pulley 19 which in turn rotates the pinion 17 which is in mesh with pinion 16 carried

on the shaft 15. As the pinion 16 rotates, the arm 14 carried thereby revolves, and since the arm 14 carries the pinion 12, it will be seen that the pinion 12 revolves within 5 the plate 10. Since the plunger 25 is supported by the support 23 carried by the pinion 12, it is obvious that as the pinion 12 is revolved within the plate 10, the plunger 25 reciprocates within the form 8.

10 From the foregoing it is obvious that due to the construction of the arm 14 and bearing member 23, the connecting rod moves in a true vertical plane to the end that an even pressure is exerted throughout the 15 tire surface of the cotton under operation, and that a rotary movement of a relatively short arm is converted into a reciprocating movement. The letter A as shown by the diagrammatical figures illustrates the movement of the shaft 23' while the arrow as indicated by the letter B designates the direction of rotation of the gear 12.

Having thus described the invention, what is claimed as new is:-

25 1. A press including a frame, a form positioned on the frame, a reciprocating plunger moving in the form, a connecting rod having connection with the plunger, a stationary plate secured to the frame and having 30 internal teeth, a pinion in mesh with the internal teeth, an arm having connection with the pinion, a bearing carried by the pinion, said connecting rod having its upper extremity journaled in the bearing whereby 35 rotary movement of the pinion will impart

a reciprocating motion to the connecting rod and plunger, and means for operating the pinion.

2. A press including a frame, a form positioned on the frame, a reciprocating plunger carried by the frame and adapted to move into the frame, a stationary plate secured to the frame, said plate having internal teeth, a pinion adapted to move within the plate, means for operating the pinion, 40 a connecting rod connecting the plunger and pinion, and means for connecting the connecting rod to the pinion, whereby movement of the pinion causes the plunger and connecting rod to reciprocate.

3. A press including a frame, a form positioned on the frame, a reciprocating plunger movable within the form, a connecting rod having rigid connection with the plunger, a stationary plate on the frame, said 55 plate having teeth, a pinion cooperating with the teeth of the plate, whereby movement of the pinion causes the pinion to move within the plate, said connecting rod having pivotal connection with the pinion, and said 60 plunger and connecting rod adapted to reciprocate when rotary movement is imparted to the pinion.

In testimony that I claim the foregoing as my own, I have hereto affixed my signature in the presence of two witnesses.

MARSHALL T. GOFORTH.
